UNITED STATES PATENT OFFICE.

GUSTAVE C. OSTERMANN, OF SYRACUSE, NEW YORK, ASSIGNOR TO SYRACUSE STEAM GAUGE MANUFACTURING COMPANY, OF SYRACUSE, NEW YORK, A CORPORATION OF NEW YORK.

STEAM-PRESSURE GAGE.

No. 918,900.

Specification of Letters Patent. Patented April 20, 1909.

Application filed November 5, 1907. Serial No. 400,844.

To all whom it may concern:

Be it known that I, GUSTAVE C. OSTERMANN, of Syracuse, in the county of Onondaga, in the State of New York, have invented new and useful Improvements in Steam Pressure Gages, of which the following, taken in connection with the accompanying drawings, is a full, clear, and exact description.

This invention relates to certain improvements in steam pressure gages involving the use of a hollow segmental spring having one end fixed and communicating with the steam inlet and its other end closed and free to move radially under the pressure of the steam and connected to a suitable indicating finger to actuate the latter around a dial.

I am aware that it is common to employ a single hollow segmental spring extending through the greater portion of a circle in which the free closed end extends downwardly to a plane some distance below the highest point of the segment thereby forming a pocket in which the water of condensation accumulates and becomes permanently retained therein so that during freezing weather when the steam pressure is low, the water in the pocket freezes and bursts the adjacent portion of the spring thus impairing the device to such an extent as to necessitate frequent repairs if not its replacement by a new spring. Furthermore it is found that this pocket of water detracts to a perceptible degree from the sensitiveness of the spring under low steam pressure.

My main object, therefore, is to avoid these objectionable results by terminating the free end of the spring segment at substantially the highest point of its arc thereby allowing the water of condensation to readily flow back through the inlet as the temperature and steam pressure lowers and thus avoiding any freezing or bursting of any part of the segment.

Another object is to provide for the adjustment of the connection between the free end of the spring and actuating mechanism for moving the index finger whereby the throw of the spring under predetermined pressure may be made to correspond with that indicated by the finger upon the dial.

Other objects and uses will be brought out in the following description.

In the drawings—Figure 1 is a front elevation of a steam gage embodying the various features of my invention, portions of the

glass plate and dial plate being broken away to show interior mechanism. Fig. 2 is a similar face view partly in section showing the glass plate and dial plate as removed and also showing the hollow spring segment in section. Fig. 3 is a vertical sectional view taken on line 3—3, Fig. 1, and Fig. 4 is a detail sectional view taken on line 4—4, Fig. 2.

As shown in the drawings this device comprises essentially a circular case or housing —1— having its front end open and threaded externally for receiving a bezel or threaded ring —2—, the latter being adapted to receive and support a glass plate —3—. The front interior portion of the case —1— is provided with inwardly projecting lugs or ears —4— and —5— which in this instance are located diametrically opposite each other for receiving and supporting a thin dial —6— having a circular row of graduations upon its front face which are properly marked to indicate the number of pounds per square inch of steam pressure exerted in the boiler or other steam chamber to which the gage is attached.

The bottom side of the case —1— is formed with an aperture —7— through which is passed a threaded nipple —8— adapted to be screwed to any pipe or steam chamber not shown, the inner end of said nipple being provided with an enlargement or head —9— which is secured to the boss —4— by suitable fastening means as screws —10—.

The tubular nipple —8— is provided with a central lengthwise passage —11— having a lateral offset —12— communicating at one end with a hollow segmental spring —13—, said spring being usually of greater transverse width than radial depth and is substantially semi-circular in form, its open end being rigidly secured to the head —9— in communication with the lateral passage —12— while its upper end terminates at substantially the highest point in its arc and is closed by a suitable plug or cap —14— which together with the remaining portions of the spring are spaced apart from the interior walls of the casing and mechanisms actuated thereby to allow ample radial movement or extension of the free end of the spring under steam pressure. The particular feature of this part of my invention is that the spring is substantially semi-circular and that it terminates at substantially the highest point of its

are to prevent the formation of a water pocket and to allow the water of condensation to readily flow back through the inlet —11—. This spring is normally concentric with the axis of the casing —1— and also with the axis of a central shaft or spindle —15— which is arranged in a horizontal position and is journaled in upright supporting arms —16— rising from and secured at 10 their lower end to the head —9—.

Secured to the spindle —15— between the arms —16— is a pinion —17— meshing with a segmental toothed rack —18— which is formed upon one arm of a bell crank lever 15 —19—, the latter being pivoted upon a supporting spindle —20— resting in the base of the arms —16—. The bell crank —19— lies wholly below the pinion —17—, the toothed rack being formed on the upper end 20 of one of the arms while the lower arm is provided with a clamping screw or stud —21— which enters a slot —22— in an adjustable arm —23—, the latter being connected by an upright link —24— to the head or cap —14— 25 on the free end of the spring —13—. The slotted arm —22— receives the pivotal pin —20— and also the clamping screw —21— which serves to hold the arm in fixed relation to the bell crank lever —19— although the 30 arm —23— may be adjusted along the lower arm of the bell crank lever to throw the lower end of the link —24— nearer to or farther from the pivotal pin —20— of the bell crank lever for a purpose presently described. 35 Secured to the front end of the spindle —15— is an index finger —25— which travels around the dial —6— accordingly as the spring —13— is expanded or contracted under varying steam pressures. 40 The lower and upper ends of the link —24— are pivoted respectively to the auxiliary bar —23— and free end of the cap or plug —14— by suitable pivotal screws —28— and —29—, the bar —23— when secured in 45 place forming an adjustable part of the bell crank lever and permits the adjustment of the lower end of the link —24— relative to the fulcrum —20— to vary the leverage between the free end of the spring —13— and 50 bell crank lever so that the movement of the spring —13— under a given steam pressure may cause a corresponding movement of the index finger —25— to the proper graduation upon the dial —6—. 55 In operation, steam is admitted through the inlet —11— to the hollow spring —13— and operates to distend or expand the seg-

ment more or less according to the pressure, the greater movement being imparted to the free end of the segment which in turn transmits similar motion to the pinion —17— and index finger —25— through the medium of the link —24—, the bell crank lever —19— and toothed rack —18—, thereby causing the index finger —25— to travel around the 60 graduations on the dial —6— to indicate the degree of steam pressure per square inch exerted at the inlet —11— or within the boiler or steam chamber to which the gage is attached. 65

The essential feature of the invention, however, lies in the termination of the free end of the spring segment at the highest point of its arc so as to avoid water pockets and permit the water of condensation to 70 flow back through the inlet and in addition to this the adjustment of the connections between the free end of the spring and bell crank upon which the toothed rack for operating the pinion is mounted. 75

What I claim is:

In a steam gage, a circular case having an opening in its bottom, a threaded nipple extending through said opening and provided with a head secured to the bottom of the 85 casing, said nipple being provided with a steam inlet passage, a pair of arms secured to and rising from the head, a dial secured in the front side of the case, a spindle journaled in the arms, an index finger secured to 90 the spindle and movable around said dial as the spindle is rotated, a pinion on the spindle between said arms, a bell crank lever fulcrumed upon and between said arms below the spindle and having an upright arm provided with a toothed rack engaging with said 95 pinion, said bell crank lever having a lower arm extending laterally from the fulcrum, an auxiliary arm adjustably secured to said lower arm, a hollow segmental spring having 100 its lower end secured to the head and communicating with the inlet, said spring rising from the head substantially concentric with the spindle and having its upper end terminating at approximately the highest point of 105 its arc, and a link connecting the upper end of said spring with the adjustable arm of the bell crank lever.

In witness whereof I have hereunto set my hand this 26th day of October 1907.

GUSTAVE C. OSTERMANN.
